CLIP, FASTENER, AND THE LIKE

Charles Williamson Barclay, Liverpool, England

Application March 9, 1948, Serial No. 13,785
In Great Britain April 2, 1947

1 Claim. (Cl. 248—62)

1

This invention concerns so-called "pipe clips," that is to say, clips for positioning and securing longitudinally extending elements such as pipes, bars, electric cables and the like.

One object of the invention is to provide a pipe clip which is installed with expenditure of a minimum amount of effort and application of a minimum amount of skill.

Another object is to provide a pipe clip having an improved appearance.

Another object is to construct a two part pipe clip comprising a base and a saddle, said parts being in the form of pressure die-castings.

A further object is to enable the saddle to be secured to the base without application of a bolt or the like whereby longitudinal displacement between the base and saddle is prevented.

A still further object is to provide a pipe clip in which after assembly, no fixing screws are visible.

Yet another object is to enable the pipe clip to readily accommodate to longitudinally extending elements of slightly varying diameter.

Yet a further object is to improve the state of the art. These and other objects will become apparent from the following detailed description, of a preferred form of pipe clip and of two modifications thereof, with reference to the drawings annexed hereunto.

In the drawings:

Fig. 1 is a perspective view of the pipe clip base shown on an enlarged scale;

Fig. 2 is a plan of the same base;

Figs. 3, 4 and 5 are respectively a left end elevation, an inverted plan and a side elevation of the same base;

Fig. 6 is a reversed perspective view on an enlarged scale of the saddle which with the base illustrated in Figs. 1—5 constitute a complete pipe clip in accordance with the invention.

Figs. 7, 8, 9 and 10 are respectively an inverted plan, a right end elevation, a left end elevation and a side elevation of the saddle illustrated in Fig. 6;

Fig. 11 is an inverted horizontal section on the line XI—XI of Fig. 5 but showing a relative positioning of the base and the saddle as the two parts are about to be inter-engaged;

Fig. 12 is a reversed perspective view of a slightly modified form of base shown on the same scale as the view of Fig. 1; and

Fig. 13 is a reversed perspective view showing a slightly modified form of saddle on the same scale of the view of Fig. 6.

A preferred form of pipe clip is constituted by base generally designated 1 and a saddle gen-

erally designated 2. A base (Figs. 1 to 5) is preferably formed as a pressure die-casting from a zinc base alloy. The base comprises a central plate-like portion 1a and two side portions 1b. These side portions are symmetrical i. e. one is a mirror image of the other.

The depth of the side portion 1b is rather more than twice the depth of the central portion 1a. It presents a partially semi-cylindrical side face 1c. The base thus presents a continuous flat lower surface 1d (Fig. 4) and flat upper surfaces 1e and 1f lying respectively in planes containing the said lower surface. The side portions 1b each present an inner surface 1g disposed at right angles to the surface 1f so that there is formed a parallel sided groove bounded by two surfaces 1g and surface 1f extending over the base. This groove is adapted to receive part of a pipe or the like and to be positioned longitudinally relative to the axis thereof. The central portion of the base has a transversely extending slot 1h therein; this slot has its upper edge bevelled at 1j.

Each side portion 1b has a groove 1i of width extending through about one third the depth of the said side portions disposed at mid-height thereof and extending from one end face to about one third the distance separating the end faces from the other end face, and from a central line of the semi-cylindrical side face 1c to just beyond the plane joining the ends of said semi-cylindrical side face. The roots of this groove, which are thus disposed approximately at right angles to one another, may both have radiused profiles or may both have plane surfaces. In the base shown the transverse groove roots are radiused and the longitudinal extending roots are plane. The said longitudinally extending roots may each be slightly inclined to provide a taper whereby its commencement at the side face lies about $\frac{1}{1000}$ to $\frac{1}{1000}$ of an inch nearer to the base centre than those at the end of said taper near the root termination. (This taper is shown considerably exaggerated in Figs. 2 and 4.) Between the taper end and the groove root termination there is a recess 1k extending transversely at the base towards the centre thereof and conveniently formed by a casting core which leaves a parallel sided groove 1m in the surface 1g of each side portion of the base.

Material is also absent or removed from the groove to the upper surface of each side portion in the shape of a quadrant in plan. This removed quadrant extends from that end face having a groove termination almost up to a medial plane across the base to terminate in a convexly

radiused surface in extending depthwise of the base, and from the semi-cylindrical side face $1c$ to a region approximately central of the groove also terminating in a convexly radiused depthwise extending surface $1o$.

The saddle 2 comprises an arched central portion $2a$ and two side portions or haunches $2b$ and is at its side portions of shape generally complementary to that of the base 1 . The curvature of the arched portion $2a$ is selected so that said arched portion is of constant thickness and of internal shaped complementary to the pipe or the like to be secured in the assembled pipe clip. Each haunch $2b$ comprises a relatively thin upper part $2c$ having a depending quadrant shaped web $2d$ in an outer corner thereof and a flange $2e$ below the web; this flange is of shape adapted to be received in the aforementioned groove $1i$ in the corresponding side portion $1b$ of the base.

The flange $2e$ is thus of generally quadrant shape and is bounded by a radiused transverse extending depthwise surface $2f$ which is complementary to the radiused groove root of the groove $1i$, and an approximately plane surface $2g$ which is disposed depthwise and extends longitudinally of the saddle 2 . The surfaces $2g$ and $2f$ meet in a projection $2h$. This projection may be regarded as an extension of the surface $2f$ in an inward direction and is adapted to ride into the recess $1k$ constituted by the lower end portion of the groove $1m$ where said portion intersects the plane surfaces groove root of the groove $1i$.

In operation or use the base is first fixed to a surface, such as a wall, by a wood screw or a bolt of the shank passes through the slot $1h$. The length of the slot facilitates alignment and lateral positioning of the base. The pipe or other longitudinally extending element is then positioned on the base and the saddle is placed over the element in a position relatively to the base somewhat as indicated by the relationship of Figs. 5 and 10.

The saddle is moved longitudinally of the element until each flange $2e$ becomes engaged in the appropriate groove $1i$ and relative movement is continued until the projections $2h$ over-ride the ends of the tapered groove root surfaces and enter recesses $1k$.

The dimensions of the base and saddle are so selected that a temporary distortion of the saddle, largely in the form of flexure in the central arched portion $2a$ thereof, obtains as the projections ride up the tapers. It has been found that the casting possesses sufficient resilience to allow such distortion to take place without permanent deformation, and a pronounced audible "click" is noticeable on full engagement of the two parts of the pipe clip.

Alternatively or additionally the locking of the saddle to the base may be effected by outward upsetting of protrusions $1p$ (Fig. 12) so as to positively impede withdrawal of each flange $2e$ from the appropriate groove $1i$.

Longitudinally extending angularly spaced ribs $2r$ (Fig. 13) may be provided on the saddle to provide additional gripping effect in the external surface of the element and to permit of accommodating elements of slightly varying diameters.

Clearly certain portions of the base and saddle are mutually variable or interchangeable. For

instance there may be projections on the base adapted to engage in recesses at the ends of tapered surfaces on the saddle.

The base may bend additionally to or instead of flexure of the saddle.

The ribs $2h$ are only shown as extending through part of the length of the central portion of the saddle but obviously they may extend throughout the full length thereof.

The base may have a part-cylindrical element-receiving groove instead of a straight-sided groove as shown.

The invention also includes the concept of multiple bases and saddles for accommodating a plurality of laterally spaced elements, and combined saddles and bases for use in mounting one element above and spaced from another element.

Although castings are preferred, the parts may be moulded or forged or pressed or otherwise fabricated.

I declare that what I claim is:

A pipe clip comprising two interengaging members, namely a base and a saddle, symmetrical side portions on said base partly defining a pipe-receiving volume centrally and longitudinally from one face thereof, symmetrical side portions on said saddle, a raised portion on said saddle defining a pipe-receiving volume centrally and longitudinally from one face thereof, each portion on both said base and said saddle being recessed, intermediate vertically-extending longitudinal and transverse root surfaces meeting in substantially a right angle to define on the one member a reduced neck connecting parallel upper and lower flanges on each said side portions and to define on the other member a groove between parallel upper and lower flanges of each said side portion, said parallel flanges forming the faces from which extend said pipe-receiving volumes being on the one member formed to fit into said groove on said other member, and on the other member formed to receive said reduced neck on said one member, said interengaging members then forming a whole which is continuous in outline, and means to lock the two interengaging members together, said means comprising projections on the groove-fitting flanges on said one member and slots in said grooves in said other member, the projections being capable of engaging the slots by snap action.
